CLAIM

The ornamental design for a toothpaste product package with surface indicia, as shown and described.

DESCRIPTION

FIG. 1 is a perspective view of a toothpaste product package with surface indicia showing our new design;

FIG. 2 is a front view of a toothpaste product package with surface indicia showing our new design;

FIG. 3 is a top view of a toothpaste product package with surface indicia showing our new design;

FIG. 4 is a rear view of a toothpaste product package with surface indicia showing our new design;

FIG. 5 is a bottom view of a toothpaste product package with surface indicia showing our new design;

FIG. 6 is a right side view of a toothpaste product package with surface indicia showing our new design; and,

FIG. 7 is a left side view of a toothpaste product package with surface indicia showing our new design.

The broken lines shown in the drawings depict portions of the toothpaste product package that form no part of the claimed design.
